UNITED STATES PATENT OFFICE.

GEORGE W. McCORMICK, OF NEWARK, NEW JERSEY, ASSIGNOR OF ONE-HALF OF HIS RIGHT TO NICHOLAS R. HARING, OF SAME PLACE.

LAMP-WICK.

SPECIFICATION forming part of Letters Patent No. 224,203, dated February 3, 1880.

Application filed November 15, 1879.

To all whom it may concern:

Be it known that I, GEORGE W. McCORMICK, of the city of Newark, in the county of Essex and State of New Jersey, have invented 5 certain new and useful Improvements in Lamp-Wicks; and I do hereby declare the following to be a full, clear, and exact description of the invention, such as will enable others skilled in the art to which it appertains to make and 10 use the same, reference being had to the accompanying drawing, and to letters of reference marked thereon, which form a part of this specification.

The object of this invention is to produce an 15 increased amount of light by the expenditure of a given quantity of oil, and to prevent the overflow of oil upon the outside of the lamps as produced by the wicks heretofore used.

The invention consists, first, in a lamp-wick 20 that has been submerged in a strong solution of nitrate of potash and alum, and allowed to dry, thus having formed in and upon said wick crystals of the combined salts; second, in the wick, as above prepared, combined with 25 a roll of loose or free cotton wadding, in the manner and for the purposes hereinafter more fully set forth.

Referring to the accompanying drawing, which clearly illustrates my invention, letter 30 A represents the lamp-wick, and B the roll of loose cotton wadding before mentioned, which has been secured to said wick at about the center, leaving the ends thereof free, as indicated.

The crystallized salts in and upon the lamp-wick have the effect to harden said wick, making it less porous, thereby lessening the capillary attractive force, and thus, by not allowing a too profuse supply of oil to the flame, 35 prevent the oil from overflowing upon the lamp. The salts also, by preventing a crust from forming upon the burning end of the wick, increase the brilliancy of the flame and prevents it from smoking. Again, the superfluous

supply of oil consequent upon the use of the 45 ordinary wicks reduces the temperature of the flame and tends to decrease the production of gaseous vapor, thereby lessening the illuminating power of the flame. My wick, however, by only allowing a sufficient supply of 50 oil for the evaporating process, overcomes this grave defect.

The salts used in my wick are not solvent in kerosene-oil.

The loose cotton wadding previously mentioned acts as a filter to the oil, preventing any sediment or other impurities from gaining access to or clogging the wick, thus interfering with the illuminating power of the light.

It will therefore be evident that a lower 60 grade of oil than is commonly used can be employed, thus saving expense.

In connecting the wick with the cotton wadding it is necessary that the wick be sewed thereto and fastened loosely, as indicated at c 65 in the drawing, so as not to obstruct its attractive power.

I do not claim, broadly, the combination of a lamp-wick with cotton wadding; but

What I do claim, and wish to have secured 70 by Letters Patent, is—

1. A lamp-wick having been saturated in a solution of nitrate of potash and alum and subsequently dried, thereby leaving the crystals in and upon said wick, substantially as and for 75 the purposes specified.

2. The combination of the lamp-wick, prepared in the manner herein described, with a roll of loose or free cotton wadding, one end of said wick being sewed to said cotton wadding, as and for the purposes set forth.

In testimony that I claim the foregoing I have hereunto set my hand this 10th day of November, 1879.

GEORGE W. McCORMICK.
